ELECTRICAL ALARM FOR THERMOSTATS

Application filed August 15, 1927. Serial No. 212,987.

This invention comprises an improved electrical alarm for thermostats and has for one object to provide a device of this character which may be attached to a conventional type of incubator to co-operate with the damper regulating lever thereof and adapted to sound at predetermined maximum and minimum temperatures within the incubator.

Another object is to provide a device of this character employing a contact carrying member having movable contact members mounted in spaced relation thereon and adapted to selectively co-operate with the damper regulating lever of the incubator for sounding the alarm and wherein the said contact carrying member will be bodily movable to simultaneously adjust the said contact members relative to the said lever for regulating the instant of contact therebetween.

Another object is to provide a device of this character wherein each of the said contact members may be independently adjusted upon the contact carrying member and thus further regulate the instant of contact between the damper regulating lever and the said contact members.

Another object of my invention is to provide said movable contacts in a form adapted to yieldingly engage said damper regulating lever so as to permit said lever to have its full amplitude of movement irrespective of the setting of the said contact members relative to said lever, thereby favoring the precise and prompt regulation of the temperature within the said incubator.

With the above and other objects in view, my invention consists in the combination and arrangement of parts hereinafter described and claimed, and more particularly illustrated in the accompanying drawings, wherein

Figure 1 is a front elevation of my improved alarm showing the device applied to a conventional type of incubator, the body

of which is shown in section, and a diagrammatic alarm operating circuit being shown in connection with the device.

Figure 2 is a sectional end view along the line 2—2 of Figure 1, the damper being removed.

Figure 3 is a fragmentary plan view of Figure 1.

Figure 4 is a view along the line 4—4 of Figure 1, showing the contact carrying arm with the movable contact members mounted thereon, the damper regulating lever being shown as raised and engaging the upper of said contact members.

Figure 5 is a detail of one of the contact members.

Figure 6 is a sectional view along the line 6—6 of Figure 1.

Referring now more particularly to the drawings, I show a conventional type of incubator 10, having a bracket 1 upon which is pivotally mounted a damper regulating lever 11, which in the embodiment shown is made of conductive material, and which is controlled by a thermostat 12 through a rod 2 in the usual manner, and is provided, at its free extremity, with a damper rod 3 pivotally connected to a damper lever 4, pivoted at one end to a bracket 5 on the incubator wall, and having its other end engaged with a plunger 6 depending from a damper 13 adapted to fit over the upper end of the lamp flue 14, so that, as the said damper is raised from said flue, the incubator will be ventilated and cooled, and as the damper is lowered to said flue, the incubator will be warmed. The thermostat 12 is supported interiorly the incubator 10 by a bracket 7 (Figure 1).

In carrying out my invention, I employ a bracket 15 adjustably mounted on the incubator 10 as by screws 16 engaging slotted holes 17 provided in the right angularly extending flange 18 of said bracket. Similar slotted holes 17 are also provided in the

body of the bracket adjacent to said flange, whereby said bracket may be mounted in any convenient manner on said incubator. The said bracket 15 terminates in spaced and parallel fingers 19, and each of said fingers has a longitudinally extending slot 20; outstanding flanges 21 are provided on each finger spaced from and parallel to said slot 20. In the embodiment shown, the bracket 15 is mounted so as to have the fingers 19 extending vertically.

A base 22, constructed of conductive material, is adjustably mounted on the bracket 15 as by bolts 23 passing through apertures 32 in said base and extending through said slots 20; the nuts 24 of said bolts engage the flanges 21 and are thus prevented from turning when said bolts are tightened. By this means the base 22 may be adjusted on the incubator so as to properly position the contacts 34^a and 34^b hereinafter described relatively to the regulating arm 11. In the embodiment shown, the base 22 extends horizontally, but if desired the said base may 25 extend vertically, and an aperture 32^a is provided in the base 22 for this purpose.

A bolt 25 is mounted through a block of insulating material 9 which is mounted on the base 22, and the bolt 25 is conductively connected to a switch 26 also mounted on said insulating block 9. The bolt 25 and switch 26 are thus insulated from the base 22. The head of the bolt is spaced from the block 9 by a metal sleeve 25^a on which is slidably mounted a slotted bar 27 of conductive material pivotally engaging a conductive bracket 28 adjustably mounted on the damper regulating lever 11. By the means described, the said lever 11 is conductively connected to the said switch 26 through the sleeve 25^a and the bolt 25.

A contact carrying arm 8 is mounted on said base 22 and extends right angularly thereto. Aligned upper and lower slotted holes 29 are 45 provided in said arm 8, and an outstanding flange 30 is provided on said arm spaced from and parallel to said slotted holes 29. Pins 31 slidably engage said slotted holes 29, and each pin threadedly engages a nut 33, for the purpose of positioning said pin in said slotted hole. The flange 30 prevents the turning of said nut 33 when said pin 31 is rotated, as by its knurled head 31^a, for the purpose of securing said pin in said slotted hole 29 and 55 thus to said arm 8.

L-shaped movable contact members 34^a and 34^b are spaced above and below said lever 11, respectively, and each comprises a single piece of conductive material having a contact finger 35 bent right angularly from the body of said member, and, also, spaced upstanding ears 36 are formed medially of the body of said member and extend in a direction oppositely to said finger 35. The said ears 36 have 55 aligned apertures 37 whereby said contact

member may be journaled on the pin 31. By the means described, the said contact members may be adjustably positioned and secured on said contact carrying arm 8 relatively to the normal operating position of the lever 11.

The end 42 of each of said contact members oppositely of said finger 35 is adapted to engage set screws 38^a and 38^b, each threadedly engaging brackets 39 extending from the base 22 above and below said lever 11, respectively. A slotted aperture 40 is provided in said base 22 and the lever 11 is passed freely therethrough, the length of said slotted aperture being sufficient to permit said lever 11 to have its full amplitude of movement in regulating the temperature within said incubator whereby said lever is thus air-insulated from the base 22. In the embodiment shown the said slotted aperture 40 is formed by striking out said brackets from the material of said base, the brackets thus being positioned at the top and bottom of said aperture.

The lower contact member 34^b is provided with a counter-weight 41 on the end 42 thereof, for the purpose of keeping said end normally in engagement with the set screw 38^b, which in this case extends upwardly from its bracket 39. The weight of the contact finger 35 of the upper contact member 34^a will keep the end 42 of said contact member in engagement with the set screw 38^a, which in this case extends downwardly from its bracket 39. By suitably adjusting the set screws 38^a and 38^b the ends 42 of the contact members may be raised or lowered so as to cause the said contact fingers 35 to take any desired relation with respect to the lever 11.

An electrical terminal 43 is mounted on the base 22, and detachably connected thereto is 105 a wire 44 which leads to a battery 48 or other suitable conveniently located source of electrical energy. Leading from the battery is a wire 45 which is connected to one terminal of a suitable alarm 46, and leading from the 110 other terminal of the alarm is a wire 47 which is detachably connected to the switch terminal 26^a mounted on and conductively connected to the switch 26.

In use, the switch 26 being closed, the movement of the damper regulating lever 11 is controlled by the thermostat 12 through the rod 2, and it will be seen that when the free extremity of said lever is moved upwardly 120 to actuate the damper 13, through the rod 3 and lever 4, to ventilate the incubator so as to reduce the temperature therein, the said lever is adapted to engage the contact finger 35 of the upper contact member 34^a, thereby 125 establishing an electrical circuit so that current will flow from the battery through the wire 45 to the alarm 46, thence through the wire 47 to the terminal 26^a and switch 26 and thru the bolt 25, sleeve 25^a, slotted bar 27, bracket 28, lever 11, contact 34^a, base 22, ter- 130

5 minal 43 and wire 44 to the battery. Consequently, the alarm will be automatically sounded at such time as the temperature of the incubator reaches a maximum sufficient to cause the regulating lever to be raised to a predetermined point. But, by the construction, 10 of the contact member 34^a, as described, the upward movement of the lever 11 is not limited by the engagement thereof with said contact; if conditions require the same, said lever 11 may be further moved upwardly by the thermostat 12, whereupon the contact finger 35 will yieldingly engage said lever 11 as by said contact member rotating about the 15 pin 31, thus permitting the further upward movement of said lever. After the lever has been so raised and the temperature within the incubator is reduced, the free extremity of the damper regulating lever will be lowered 20 so as to move toward the flue 14 to close the same by means of the damper 13, and is adapted to engage the lower contact member 34^b. Current will then flow, as before described, except that the contact member 34^b will now 25 serve as the conductive medium between the base 22 and the lever 11. The lever 11, after engaging the contact 34^b, may be further moved downwardly by the thermostat 12; the contact finger 35 will yieldingly engage 30 the lever 11 as by the contact member 34^b rotating on the lower pin 31, thus permitting the further downward movement of the lever.

Consequently, the alarm 46 will be automatically sounded whenever the lever 11 is 35 moved by means of the thermostat 12 a predetermined distance. Thus, for example, the upper contact member 34^a and, consequently, the contact finger 35 thereon, may be adjusted on the contact carrying arm 8 so that as said lever 11 is moved upwardly by said thermostat, the said contact finger 35 of said contact member will engage the said lever 11 when the temperature within the incubator is, for 40 example, 104 degrees, whereupon the electrical circuit will be closed and the alarm will be sounded, but the lever 11, if necessary, may further rise, as described, so as to quickly bring the temperature of the incubator to 45 normal. Conversely, the lower contact member 34^b and, consequently, the contact finger 35 thereon, may be adjusted on the contact carrying arm 8 so that as said lever 11 is moved downwardly by said thermostat, the said contact finger 35 of said contact member will engage said lever 11 when the temperature within the incubator is, for example, 50 101 degrees, whereupon the electrical circuit will be closed and the alarm will be sounded, but the lever 11, if necessary, may be caused 55 to have a further downward movement, as described, so as to quickly bring the temperature of the incubator to normal. It will be seen, therefore, that by my construction, an alarm is sounded as soon as the temperature 60 within the incubator departs from the safe

limits of temperature range of operation thereof, while at the same time, the thermostat is permitted to freely operate the damper in the usual manner, so as to promptly and with out hindrance, bring the temperature 70 within the incubator to its proper point.

In the embodiment shown, the base 22 may be vertically adjusted relative to the incubator so as to simultaneously adjust the instant of contact between the regulating lever 11 and each of the contacts 34^a and 34^b, for controlling the sounding of the alarm at various predetermined maximum and minimum temperatures within the incubator, but preferably the permissible range of temperatures will be determined by adjusting the set screws 38^a and 38^b for maximum and minimum temperatures, respectively. When it is desired to render the alarm inoperative, it is only necessary to open the switch 26, without disturbing the setting of the device in any manner.

While I have herein shown and described my invention in connection with a thermostatically controlled incubator, I do not wish to be limited to the precise construction shown in the employment of my invention. It will be readily seen that my invention consists of a device which may be used with any thermostatically controlled device, such as ventilators or valves for letting heat in or out of a chamber or room, such as for drying ovens, and the like. My invention is also adapted for use with a thermostat for various purposes generally so as to give an alarm whenever the temperature rises or falls to a predetermined point, such as, for example, a fire alarm for a home or buildings, the existence of a fire serving to cause the thermostat to operate the alarm, in a manner similar to that described. It will be seen that, if desired, the thermostat may be enclosed in a heat resisting cabinet so that the alarm would only be sounded when the heat was sufficient to overcome the resistance of the cabinet and thus operate the thermostat. Other uses of my invention will be readily apparent to those skilled in the art.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

The combination with an alarm circuit of an oscillating lever of conductive material, of a base of conductive material, a conductive bolt insulatably mounted on said base, a conductive bar slidably engaging said bolt, a conductive bracket adjustably mounted on said lever and pivotally engaging said bar, a conductive contact member adjustably mounted 125 130

on said base for rotation in the plane of oscillation of said lever, a finger formed on said contact member adapted to operatively engage the said lever for the rotation of said contact, and means for adjustably spacing said finger with respect to the normal operating position of said lever, said finger forming one of the terminals of said alarm circuit, and said lever forming the other of said terminals.

10 In testimony whereof I affix my signature.
HENRI PIQUET.
